UNITED STATES PATENT OFFICE.

HARRY H. HUBBARD, OF GRAND RAPIDS, MICHIGAN, ASSIGNOR TO THE EGRY REGISTER COMPANY, OF DAYTON, OHIO, A CORPORATION OF OHIO.

AUTOGRAPHIC REGISTER.

Application filed April 2, 1925. Serial No. 20,060.

My invention relates to autographic registers.

It is the object of my invention to provide an autographic register capable of 5 aligning prior to each writing operation a plurality of sheets, and of leading said sheets in aligned condition during the writing operation without the use of any means for entering the sheets, and without the use of 10 any means such as aligning pins, pin wheels and the like.

It is my object to provide in particular such a register which is adaptable to use sheets in packs.

15 It is my object to eliminate the use of perforated paper which has been found objectionable for a variety of reasons as customarily used in autographic registers. Paper with marginal perforations is particularly 20 objectionable, but heretofore found necessary in some classes of registers which use pin wheels or other pin mechanism for aligning and actuating a plurality of such sheets through an autographic register.

25 It is my especial object to provide an autographic register which will engage with a plurality of sheets, eject them from the register a predetermined distance, release the sheets, align the sheets by means of a crease, 30 fold, bend, or a series of minor transverse perforations, bringing this predetermined mark aligned transversely of the sheets to a predetermined dead line or alignment line by moving the sheets forwardly to the line 35 or pulling them back to the line, thus aligning the sheets at each operation, and upon alignment regripping the sheets.

40 It is my object in such a combination to grip the sheets by the moving ejecting members and at a time when such moving members are stationary so that at the moment of gripping of the aligned sheets the normally 45 rotating ejecting members will be stationary and therefore not liable to shift the sheets when the engagement is made prematurely. In other words, the engagement for regripping the sheets is a clamping engagement of members which are not rotating and which 50 cannot rotate at that moment, being positively held against rotation, thus preventing the premature slipping of one of the sheets over the others due to the fact that members which rotate and grip at the same time have

a tendency to move the sheet with it and they could not eject first before the complete 55 gripping operation can take place.

In this register I provide a plurality of superimposed sheets having the customary business forms imprinted thereon in predetermined relationship to certain aligning 60 marks or means such as creases, scores, or transverse perforations to insure the bending of the sheets on predetermined lines in predetermined relationship to the forms between the forms and at spaced intervals from 65 one another and the forms. The register at each operation before the writing takes place after ejection or just at the completion of the ejection operation shifts the aligned sheets to a point where it creases, scores, or 70 minute transverse perforations will coincide and when they do coincide the sheets are then gripped without further shifting so that they will be held in aligning condition for writing. 75

It is a further object to provide a very easy means of loading so that the ordinary clerk or business man of no mechanical ability can quickly and easily load the register, bring the sheets to alignment and close up 80 the register without necessity of specially skilled experience which has been usually necessary in other registers on the market to perform the aligning and loading operations to get the register in condition for use. 85

It is an additional object of my invention to provide a register which in the event that through error in production of paper there shall be a difference in spacing between the scores or transverse minute perforations 90 thus giving some of the bills an unequal length, this machine of my invention will compensate for this error, eliminate it in the aligning operation and will prevent the accumulation of this error which would otherwise progressively throw the forms out of alignment with one another and out of exact superimposed condition. 95

Referring to the drawings:

Figure 1 is a plan view of the register 100 with the forward end of the writing table broken away and with the cover lifted;

Figure 2 is a detail of the cam mechanism;

Figure 3 is a section on the line 3—3 of Figure 1, showing the operating mechanism 105 for the aligning mechanism and for the

ejecting roller mechanism. In this view the parts are in position just at the beginning of the aligning operation;

Figure 4 is a similar view showing the aligning mechanism in position at the interval of gripping the sheets on the alignment line or dead line with the ejecting rollers in inoperative position.

Figure 5 is a strip of billing;

10 Figure 6 is a vertical sectional view on the line 6—6 of Fig. 1, looking in the direction of the arrows;

15 Figure 7 is a vertical sectional view on the line 7—7 of Figure 1, looking in the direction of the arrows; and

Figure 8 is a detail perspective view of the aligning devices in their open or rest position.

Referring to the drawings in detail, 1 is 20 the usual bed plate or bottom of an autographic register. 2 and 3 are the respective side walls of the register. To these side walls is attached the rear wall 4 and pivoted on the upper edges of the side walls 25 at the rear is the usual cover 5 having a cut away portion as at 6 to permit the writing upon the several superimposed sheets marked 7, 8 and 9. Any number of sheets may be employed. Interleaved between 30 these sheets are the usual carbon sheets 10 carried on the roll 11 in the carbon box 12. This is conventional construction and forms no part of the construction as anything of this character may be used as desired.

35 Beneath the sheets is the writing table 13 carried on the upper edges of the side walls 2 and 3 by means of the laterally projecting fingers 14 which rest in notches in the side walls on the upper edges thereof to 40 position the writing table 13 in the usual manner. Such details may be varied to suit the register and the taste of the person constructing or using the register. Mounted on the rear end of this writing table extending 45 upwardly and rearwardly in a plane above but parallel to the general plane of the writing table is a guard plate 15 used to prevent the sheets of paper from being actuated by the frictional contact of one of the reciprocal aligning plates so that the 50 only action of the plate will be upon the predetermined part of the paper desired. This assists in securing the desired results from this invention. This forward aligning 55 plate is designated 16 and consists of a flat piece of metal resting upon at its outer ends the upper edges of the side walls 2 and 3 and adapted to reciprocate within a limited degree on the top of said walls. This plate is provided with rearwardly extending and 60 supporting as well as guiding fingers 17 which rest upon and move over the top of the rear aligning and reciprocating plate 18 which likewise has its ends resting upon the 65 top of the side walls 2 and 3. The rear

edge of the forward aligning plate 16 is preferably narrow and thin or may be sharpened as at 19 in order to assist in bringing the under surface of the scored or perforated portions of the paper directly against its edge and in alignment therewith as it starts in its rearward movement thus positioned relative to these paper sheets so that they may be aligned near its edge 19 and then carried back to the aligning line or so-called dead line of alignment designated 20. The rear reciprocating plate is provided with a pair of jaws 21 above and below the plane of the edge 19 and adapted to receive between them the edge 19 of the plate 16 and to receive between the edge of the plate and the plate 18, between these jaws, the several sheets in the neighborhood of their transversely scored, folded, or perforated portions. These jaws serve to receive the ridge-like bent portions of the paper and to bring them into alignment by the forward movement of the rear aligning plate 16. Thus the sheets are brought into alignment on the dead line 20 at which the plates 16 and 18 meet with these predetermined transversely scored, folded, bent, or perforated portions of the paper sheets between them and aligned on this dead line of alignment 20.

With this understanding of the mechanism of alignment, I will explain the mechanism for operating the aligning plates and for operating in synchronism with the aligning plates the ejecting rollers which have the dual function of ejecting the sheets and of clamping them at a predetermined interval either for ejection or for holding during the writing operation. The register is operated by the usual handle 22 which is pinned to a transverse shaft 23 by the pin 24. This handle is journaled in the side walls 2 and 3 of the register. It carries on the inside of the wall 3 a master operating gear 25 which meshes with a gear 26 carried on the shaft 27 journaled in the walls 2 and 3. This gear 26 meshes with the gear 26^a on the shaft 27^a. This shaft carries the lower roller 28 which is knurled as at 29. The gear 26 meshes with another gear of small diameter 30 directly above it and carried on the shaft 31 which supports the upper roller 32 which is provided with the knurled surface 33. This shaft 31 is loosely held so that it can reciprocate in a vertical path in the upwardly extending side wall projections 34 in the slots 35 thereof. Over either end of the shaft within the upwardly projecting housings 34 are springs 36 for resisting the upward movement of the roller 32 and for yieldingly maintaining it in engagement with the lower roller or sheets therebetween when the upper roller is not positively held out of engagement with the lower roller or the sheets therebetween. It will be observed that the master gear 25

has its teeth cut away a portion of its periphery as at 37.

The main operating shaft 23 carries two types of cams. One type of cam designated 37^a located on either end of the shaft just within the side walls of the register operate the mechanism for lifting the upper roller bodily vertically. At this interval of lift the rollers are rendered inoperative due to the 10 fact that the blank space on the gear 25 eliminates the driving action of the gear 25 on the gears 26 and 26^a.

These cams 37 serve to lift the free ends of the levers 38 which are journalled on the 15 transverse shaft 39 on either side of the register within the side walls. When the cams 37 engage with the levers 38 and lift them they also lift the arm 40 which projects upwardly and the transversely extending arm 20 41 which projects horizontally and rearwardly between the roller shafts. The arm 41 on either side engaging in the reduced spaces 42 and 43 at the end of the rollers will lift the upper roller from engagement with 25 the sheets between it and the lower roller. Thus upon the rotation of the handle and its shaft 23 these cams 37 will at predetermined intervals lift and maintain in lifted condition the upper roller to thus render the 30 clamping or clamping and ejecting action temporarily inoperative.

The second type of cam mounted on the shaft 23 and rotating with it is the cam designated 44 which is the aligning cam. 35 This cam engages with the head 45 on the reciprocating lever 46 pivoted at 47 to the depending centrally located lever 48 which is suspended on a transverse shaft 49 carried in the side walls of the register. This lever 40 has connected at its lower end a helical spring 49^a and at its other end to the shaft 23 so that the spring 49^a constantly tends to move the lever 46 and its head 45 rearwardly against the shaft 23 and the cam 44. The spring also tends to move the entire 45 mechanism connected with the lever 48 which is the aligning mechanism into inoperative position. The cam 44 serves to move the mechanism in the other direction to the aligning position. Mounted on the shaft 49 on either end thereof and fixed to the shaft 49 is a lever 50 carrying at its upper end pivotally as at 51 an actuating rod 52 which is bent at 53 to clear the handle shaft 23. 50 The rear end of this actuating plate or rod 52 is connected at 54 to a downwardly projecting finger 55 which depends from one side of the aligning plate 16. It will be understood that a duplicate mechanism of this 55 character will be found on either side of the register within the side wall.

The lever 50 on its lower end carries the actuating plate or rod 56 which is connected at 60 to a depending finger 61 on the rear aligning plate 18.

The forward end of the register is provided with the usual hinged forward plate 62 and the sliding cover plate 63 which has fingers 64 for overlapping the forward end 65 of the cover 5. The cover is struck up 70 into a housing 66 to enclose the upper roller. At the bottom of this housing at 67 is a cutting edge against which the sheets may be torn off.

On the shaft 49 on the outside of the register is a finger piece 68 which serves to actuate the aligning plates and attended mechanism independently of the handle. This is not an essential but simply an accessory of 75 the invention.

The handle is brought to a stop by any suitable means but preferably by the method of using a pivoted stop member 69 pivoted at 70 on the outside of one wall of the register. This stop can be moved by the finger 80 of the operator so as to permit the handle to pass by. Any conventional form of handle or stop can be employed, however, as this is not an essential of my invention.

The cover 5 serves to prevent the paper 90 from rippling or buckling and maintains it in position for the aligning operation as well as protects the parts.

Method of operation.

95

To load this register I lay a pack of superimposed folded sheets lifting the free end of the sheets and inserting them between the aligning plates and then bring the aligning plates into clamping position 100 with the sheets aligned on the fold, crease, or transverse series of minute perforations and insert the forward end of the sheets between the rollers. I then bring the handle to rest against the stop whereupon the 105 sheets are clamped by the rollers and are held in aligned position. The cover can then be closed.

After the writing operation through the opening in the lid 5, the handle is rotated, 110 the sheets are ejected, and during the ejecting operation the new sheets are aligned on a new transverse crease, fold, or minute series of perforations being either drawn backwardly or pushed forwardly so that 115 such transverse line is clamped on the dead line by the aligning plates having been pulled or pushed in position just prior to which operation the rolls have released their grip on the sheets so that the sheets may 120 be freely shifted in the register. Upon the completion of this aligning operation the rollers are brought to gripping position again while the rolls are still stationary. The rolls do not turn again until after the 125 writing operation so that there can be no shifting of the sheets due to the turning of the rollers when they reengage the sheets. It will be noted that the movement of the upper roller is in a vertical plane so that 130

no transverse drag will be imparted to any of the sheets to shift them.

In the loading operation if it is desired the finger piece which is mounted on the shaft 49 may be actuated to actuate the aligning mechanism to clamp the paper into aligning position. This is an accessory and not an essential of the invention.

It will be understood that I desire to comprehend within my invention various modifications of it to meet varying conditions. I comprehend in it the use of not only folded stationery, but of rolled stationery. My invention is a laptab to the storing of records and the like and to other uses to which autographic registers are put.

It will be understood in the claims that when I refer to creased stationery I am referring to stationery that may be bent, folded, grooved, creased or perforated transversely or formed in any way so that it is adapted along a transverse line to be brought to the aligning line by the aligning plates. Such indentation or fold can be formed with the paper and the paper can be mounted on rolls instead of packs as illustrated.

The sequence of operation and the time and relation thereof is as follows:

30 The paper is ejected by the operation of the ejecting rollers until near the end of the stroke. At that time, the rollers are separated by the action of the members adapted to lift the rollers and simultaneously upon such separation, the aligning jaws begin to approach one another to grasp between the jaws the sheets of paper adjacent the lines of perforation of the paper so that the lines of perforation and the meeting line of the jaws will coincide. This results in their pushing the paper forward or pulling it backwardly so that the lines of perforation will be aligned on the meeting line of the jaws. The ejecting means being inoperative allows the paper sheets to be so moved backwardly and forwardly during aligning operation.

Having thus fully described my invention, what I claim as new and desire to secure by Letters Patent, is:—

55 1. In an autographic register using creased stationery, means to align a plurality of superimposed sheets having spaced creases along the creased line on a predetermined transverse line in the register, said aligning means consisting of members adapted to move said sheets to the aligning line engaging the sheets adjacent the creased portions.

60 2. In an autographic register using creased stationery, means for engaging creased sheets adjacent the creases therein for moving said creased sheets to a superimposed position at a predetermined point in the register so that the creases will be super-

imposed on one another and on the predetermined line, and means for clamping said sheets when aligned along the creases in the sheets.

3. In an autographic register using creased stationery, means for engaging creased sheets adjacent the creases therein for moving said creased sheets to a superimposed position at a predetermined point in the register so that the creases will be superimposed on one another and on the predetermined line, means for clamping said sheets when aligned along the creases in the sheets and means for ejecting said sheets after clamping. 70 75 80

4. In an autographic register using creased stationery, means for moving creased sheets to a superimposed position at a predetermined point in the register so that the creases will be superimposed on one another and on the predetermined line, means for clamping said sheets when aligned along the creases in the sheets, and means for ejecting said sheets after clamping, and means for freeing the sheets from clamping 85 90 or ejecting operations during the aligning operation.

5. In an autographic register using creased stationery, means for aligning said sheets along the creases at a predetermined transverse line in the register, means for clamping said sheets after alignment and after the aligning means have completed the aligning operation, and means for ejecting said sheets and for bringing other portions of the sheets to aligning position, and means for freeing the ejecting and clamping means from the sheets prior to the aligning mechanism operating so that the sheets will be loosely arranged in the register during the 105 aligning operation. 100 105

6. In an autographic register using creased stationery containing a supply of said stationery consisting of a plurality of superimposed sheets with spaced transverse creases, means for ejecting said sheets by clamping them, means to control the clamping of said sheets, so arranged that when the sheets are clamped the ejecting means is not rotating, to prevent shifting of the sheets, means for aligning the sheets on the creases at a predetermined transverse line in the machine, and a common actuating means so arranged that during the operation of the aligning means the sheets will be unclamped 115 and the ejecting means will remain stationary. 120

7. In an autographic register using creased stationery containing a supply of said stationery, consisting of a plurality of superimposed sheets with spaced transverse creases, means for ejecting said sheets by clamping them, means to control the clamping of said sheets, so arranged that when the sheets are clamped the ejecting means is not 125 130

rotating, to prevent shifting of the sheets, means for aligning the sheets on the creases at a predetermined transverse line in the machine, and a common actuating means so arranged that during the operation of the aligning means the sheets will be unclamped and the ejecting means will remain stationary, and means to maintain the paper sheets away from the aligning mechanism until the time for the aligning operation takes place to prevent premature shifting of the sheets.

8. In an autographic register using creased stationery containing a supply of said stationery, consisting of a plurality of superimposed sheets with spaced transverse creases, means for ejecting said sheets by clamping them, means to control the clamping of said sheets, so arranged that when the sheets are clamped the ejecting means is not rotating, to prevent shifting of the sheets, means for aligning the sheets on the creases at a predetermined transverse line in the machine, a common actuating means so arranged that during the operation of the aligning means the sheets will be unclamped and the ejecting means will remain stationary, means to maintain the paper sheets away from the aligning mechanism until the time for the aligning operation takes place to prevent premature shifting of the sheets, and means for maintaining the sheets in position in the register.

9. In an autographic register using creased stationery containing a supply of such creased stationery, reciprocating aligning plates adapted to permit such stationery to pass therebetween and to draw said stationery to a predetermined line along its creases by engaging the stationery on either side thereof at predetermined intervals, means for ejecting the sheets while the aligning means is inoperative, remaining in engagement therewith until the alignment operation starts, means for freeing said sheets from the ejecting means during the aligning operation and permitting the reengagement of the sheets while the ejecting means is stationary after the aligning operation, and a common actuating means for the aligning mechanism, ejecting mechanism and mechanism for freeing or clamping the sheets.

10. In an autographic register using creased stationery containing a supply of such creased stationery, reciprocating aligning plates adapted to permit such stationery to pass therebetween and to draw said stationery to a predetermined line along its creases by engaging the stationery on either side thereof at predetermined intervals, means for ejecting the sheets while the aligning means is inoperative, remaining in engagement therewith until the alignment operation starts, means for freeing said sheets from the ejecting means during the aligning operation and permitting the re-

engagement of the sheets while the ejecting means is stationary after the aligning operation, a common actuating means for the aligning mechanism, ejecting mechanism and mechanism for freeing or clamping the sheets, and a guard over that portion of the aligning mechanism over which the paper passes to prevent the paper from engaging therewith until the aligning mechanism is put into operation.

11. In an autographic register using creased stationery, means at the rear of the register for drawing the stationery to a predetermined line, arranging the sheets so that the crease will be superimposed on that line, said means consisting of reciprocating plates, a writing table, and upper and lower clamping and ejecting rollers engaging with the sheets at the end of the writing table, means for actuating said rollers except during the aligning operation, means for rendering said clamping and ejecting rollers inoperative during the aligning operation and permitting the reengagement of the rollers with the sheets in clamping position upon the completion of the aligning operation, means for returning the aligning mechanism to normal position after the aligning operation, a handle, an operating shaft, means thereon for operating the ejecting rollers, means for separating the rollers to free the sheets, and means for actuating the aligning means.

12. In an autographic register using creased stationery, means at the rear of the register for drawing the stationery to a predetermined line, arranging the sheets so that the crease will be superimposed on that line, said means consisting of reciprocating plates, a writing table, and upper and lower clamping and ejecting rollers engaging with the sheets at the end of the writing table, means for actuating said rollers except during the aligning operation, means for rendering said clamping and ejecting rollers inoperative during the aligning operation and permitting the reengagement of the rollers with the sheets in clamping position upon the completion of the aligning operation, means for returning the aligning mechanism to normal position after the aligning operation, a handle, an operating shaft, means thereon for operating the ejecting rollers, means for separating the rollers to free the sheets, means for actuating the aligning means, said means for actuating the rollers consisting of a mutilated gear, and the means for actuating the aligning mechanism and separating the rollers being spaced cams mounted on the handle shaft, and a guard over that portion of the aligning mechanism over which the paper passes to prevent them from prematurely engaging with the aligning mechanism.

13. In an autographic register using

aligning mechanism moves in one direction and the other in the other simultaneously, and aligning plates carried thereby at the rear of the register, whereby the stationery is aligned in superimposed relationship on the crease at a predetermined transverse line on the register during which the ejecting rollers are rendered inoperative and are spaced to free the sheets for alignment, and 10 yielding means for returning the aligning mechanism to normal inoperative position.

18. In an autographic register using creased stationery, means to move the stationery to a predetermined transverse line 15 so that it will be arranged in superimposed relationship on the creased lines on the predetermined line in the plane of the writing table, means for clamping and ejecting the sheets when aligned and freeing the sheets 20 during the aligning operation, and a common actuating means for successively actuating the aligning mechanism, ejecting mechanism, and clamping mechanism.

19. In an autographic register using

creased stationery, means to move the stationery to a predetermined transverse line so that it will be arranged in superimposed relationship on the creased lines on the predetermined line in the plane of the writing table, means for clamping and ejecting the sheets when aligned and freeing the sheets during the aligning operation, and a common actuating means for successively actuating the aligning mechanism, ejecting mechanism, and clamping mechanism, said stationery being arranged in a folded pack in the body of the register, being folded along the creased lines.

20. In an autographic register using continuous sheets of creased stationery, means to cause the sheets to hinge on the creases approximately at a predetermined transverse line in the register, and means to align the sheets at the hinge on the predetermined transverse line in the register.

In testimony whereof, I affix my signature.

HARRY H. HUBBARD.
